F. Fruitt, Making Barrel Heads.

N° 10,228.

Patented Nov. 15, 1853.

Fig. 1

Fig. 2

UNITED STATES PATENT OFFICE.

FRANKLIN FRUIT, OF JEFFERSON CITY, MISSOURI.

CHUCK FOR CUTTING BARREL-HEADS.

Specification of Letters Patent No. 10,228, dated November 15, 1853.

To all whom it may concern:

Be it known that I, FRANKLIN FRUIT, of Jefferson City, in the county of Cole and State of Missouri, have invented a new and 5 useful Improvement in Machines for Cutting Barrel-Heads; and I do hereby declare that the following is a full, clear, and exact description of the same, reference being had to the annexed drawings, making a part of 10 this specification, in which—

Figure 1, is a plan or top view of the machine. Fig. 2, is a face view of the chuck.

Similar letters of reference indicate corresponding parts, in each of the two figures. 15 The nature of my invention consists in holding the material of which the barrel-head is cut, by means of a chuck, having a series of centers, placed in circular form, and concentric with the periphery of the 20 chuck. Each center is provided with a spiral spring, which enables the centers, individually, to give or yield, so that the different pieces forming the barrel-head may vary in thickness, and still be firmly held by 25 the chuck, as will be presently shown.

To enable others skilled in the art to make and use my invention, I will proceed to describe its construction and operation.

A, represents a mandrel, or shaft, on one 30 end of which a face-plate, B, is secured.

C, is a mandrel, or shaft, on one end of which a chuck, D, is secured, and which chuck will be hereafter fully described. The two mandrels, or shafts, A, C, are placed 35 in line, and work or run in suitable bearings, supported by a frame, constructed in any suitable manner.

The "stuff", or material from which the barrel-heads are cut, is secured between the 40 face-plate, B, and the centers of the chuck, D.

The chuck is formed or constructed of two circular disks, (a), (b), connected by studs, (c), of such a length as to allow a requisite space between the disks. These studs are 45 screwed into the front disk, (a), and their opposite ends pass through the back disk, (b), and have nuts, (d), upon them, which nuts are screwed firmly against the outer surface of the back disk. The studs are 50 placed all around the disks, and near their edges, forming a circle, concentric with the peripheries of the disks.

Between the studs, (c), are placed centers, (e), which pass through both the front and 55 back disks. The centers have collars, (f), upon them; and between the collars and the

inner side of the back-plate, and upon each center, there is placed a spiral spring, (g). These springs, of course tend to throw the points of the centers firmly against the 60 "stuff", or material, represented by, E.

Barrel-heads are formed of several pieces; and these pieces often vary in thickness. Now, by placing the several pieces against the face-plate, B, the centers, (e), will press 65 each piece firmly against the face-plate, no matter whether it is thick or thin; for, if thick, the springs will allow the centers, against which the piece is in contact, to yield or give sufficiently to allow the perfect 70 adjustment of the piece, between the face-plate and centers; the centers holding or pressing it firmly against the face-plate. If the piece is thin, the springs will force the centers forward and against it, and with 75 sufficient pressure to keep it firmly to the face-plate.

In Fig. 2, the red lines indicate a barrel-head, and the several pieces of which it is formed. 80

It will be seen, by the above arrangement, that each piece of a barrel-head may differ in thickness from the others; and, as each center is provided with a spring, and works independently of the others, each piece may 85 be properly secured between the face-plate and chuck.

The mandrels, or shafts, A, C, are provided each with a screw, F, at their outer ends, by operating which, the face-plate and 90 chuck may be brought nearer together, or placed farther apart, as desired.

G, G, are two slides, which contain cutters, H, I, for cutting the bevels on the periphery of the head; and also, a cutter, J, for cutting 95 the head in circular form, or of the proper circumference.

The slides are moved, longitudinally, by means of levers, K, K, the tops of which are seen in Fig. 1; and they are moved, laterally, 100 by means of screws, L, L, L.

The slides and cutters, and also the manner of operating them, are well known and familiar devices, and require no further description. 105

I do not claim the slides, nor the cutters, nor any particular manner of operating them; but,

Having described my invention, what I claim as new, and desire to secure by Letters 110 Patent, is,

The chuck, D, constructed substantially

as herein shown and described, viz.,—two circular disks, (a), (b), connected by studs, (c), and centers, (e), placed between the studs; any proper number of studs and centers being used; said centers passing through both the front and back disks, (a), (b), and having collars, (f), upon them; each center being provided with a spiral spring, (g), which is placed between the collar and the 10 inner side of the back disk, (b); and by which springs, each center will yield or give,

independently of the others, so that the different pieces forming the barrel-head may vary in thickness, and still be properly adjusted and secured between the face-plate 15 and chuck, as set forth in the body of this specification.

FRANKLIN FRUIT.
